(57) **CLAIM**

The ornamental design for a bathtub caddy tray, as shown and described.

DESCRIPTION

FIG. 1 is a perspective view of a bathtub caddy tray design showing my new design.

FIG. 2 is a front view of a bathtub caddy tray.

FIG. 3 is a rear view of a bathtub caddy tray.

FIG. 4 is a left side view of a bathtub caddy tray.

FIG. 5 is a right side view of a bathtub caddy tray.

FIG. 6 is a top view of a bathtub caddy tray; and,

FIG. 7 is a bottom view of a bathtub caddy tray.

The broken lines show portions of the bathtub caddy tray that form no part of the claimed design.
